UNITED STATES PATENT OFFICE

168,055

CYCLE SADDLE

James Van Dyne Lundy, Edgewood, R. I., assignor
of one-half to Julius H. Warner, Hartford,
Conn.

Application January 22, 1952, Serial No. 18,148

Term of patent 14 years

(Cl. D90—16)

To all whom it may concern:

Be it known that I, James Van Dyne Lundy, a citizen of the United States, residing at Edgewood, State of Rhode Island, have invented a new, original, and ornamental Design for a Cycle Saddle, of which the following is a specification, reference being had to the accompanying drawing, forming a part hereof.

Figure 1 is a perspective view of a cycle saddle, showing my new design;

Figure 2 is a side elevational view; and

Figure 3 is a rear elevational view thereof.

I claim:

The ornamental design for a cycle saddle, as shown.

JAMES VAN DYNE LUNDY.
